UNITED STATES PATENT OFFICE

145,008

DESIGN FOR A VANITY CASE

Walton B. Crane, Beverly Hills, Calif., assignor to Allied Plastics Company, Los Angeles, Calif., a partnership.

Application July 30, 1945, Serial No. 121,063

Term of patent 3½ years

(Cl. D86—10)

To all whom it may concern:

Be it known that I, Walton B. Crane, a citizen of the United States of America residing in the city of Beverly Hills, in the county of Los Angeles, State of California, have invented a new, original, and ornamental Design for a Vanity Case, of which the following is a specification, reference being had to the accompanying drawings, forming a part thereof.

I claim:

The ornamental design for a vanity case, substantially as shown.

WALTON B. CRANE.
